GB 9006094215-0001 * 1/2019
 JP D1567288 * 12/2016

Primary Examiner — Paula Allen Greene(74) *Attorney, Agent, or Firm* — Suzanne Kikel, Patent Agent(57) **CLAIM**

The ornamental design for a headset, as shown and described.

DESCRIPTION

FIG. 1 is a perspective view of a headset, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left elevational view thereof; and,

FIG. 7 is a right elevational view thereof.

The trademark/logo material containing the smiling design on the headset headband attachment forms part of the claimed design and is owned by the inventor.
